UNITED STATES PATENT OFFICE.

JACOB KAMMERER, OF NEW YORK, N. Y., ASSIGNOR TO ACME WEATHER STRIP COMPANY,
A CORPORATION OF NEW YORK.

WEATHER-STRIP.

No. 915,445.

Specification of Letters Patent. Patented March 16, 1909.

Application filed May 18, 1908. Serial No. 433,460.

To all whom it may concern:

Be it known that I, JACOB KAMMERER, a citizen of the United States, residing at the borough of Manhattan, city of New York, 5 in the county of New York and State of New York, have invented certain new and useful Improvements in Weather-Strips, of which the following is a specification, reference being had therein to the accompanying 10 drawings, forming part thereof.

My invention relates to weather-strips and is particularly adapted for application to the meeting rails or check rails of window sashes.

The objects of my invention are simplicity 15 and inexpensiveness of construction, durability, prevention of rattling, and a high degree of efficiency in excluding wind, rain and dust.

Other objects and advantages will appear 20 from the following description.

My invention includes two coacting strips so shaped and related the one to the other and to the sash rails as to produce a double seal.

25 My invention more particularly includes a tongue extending into a groove and an overlapping ledge or lip closing the mouth of the groove.

My invention also includes a tongue extending 30 at an angle from the strip on one sash rail and adapted to enter a groove inclined at an opposite angle and formed by the other strip on the other sash rail.

My invention also includes other advantageous 35 features and several details of construction, as will hereinafter appear.

I will now describe my invention with 40 reference to the accompanying drawings and will thereafter point out my invention in claims.

Figure 1 is a vertical section through the meeting rails of the upper and lower windows and through the two parts of the weather-strip. Fig. 2 is a vertical section 45 of the upper rail or meeting rail of the lower sash and the portion of the weather-strip carried by it. Fig. 3 is a side elevation of the same. Fig. 4 is a vertical section of the lower rail or meeting rail of the top sash and 50 the portion of the strip carried by it. Fig. 5 is a side elevation of the same.

In the embodiment of my invention illustrated in the drawings an upper rail or meeting rail 1 of a lower sash and a lower rail or 55 meeting rail 2 of an upper sash are shown

as provided with coacting inclined meeting faces.

My invention includes complementary members or strips 3 and 4 secured respectively to the upper rail or meeting rail 1 of 60 the lower sash and to the lower rail or meeting rail 2 of the upper sash. The members or strips 3 and 4 are constructed of sheet metal bent to the required form or shape, sheet zinc being well adapted to the purpose. 65

The member or strip 3 is bent back double upon itself and has its mutually adjacent edge portions bent to form a flange 11 which seats in a slot in the sash rail 1 as shown. The outer doubled portion of the member 3 70 lies flat against the meeting face of the rail 1 which is rabbeted as shown to receive the member 3 so as to provide an even or flush surface, and the member 3 is secured to this rabbeted surface of the meeting face of the 75 sash rail 1 by nails or the like, as shown in Fig. 3. The sash rail 1 is also provided with rabbets at 5 and at 6 (see particularly Fig. 2), and the folded edge of the strip or member 3 projects beyond the edge of the rabbet 80 5 and forms therewith a groove which is parallel with the inclined meeting face of the rail 1.

The strip or member 4 has a flange 7 seated 85 in a slot in the meeting face of the lower rail or meeting rail 2 of the top sash, and has a flat portion lying against such meeting face, the meeting face being rabbeted to provide an even surface as shown in the drawings. The member 4 is secured to this rabbeted 90 surface by nails or the like as may be seen in Fig. 5. The member 4 is bent or folded upon itself to form a sealing tongue 8, which extends upwardly at an oblique acute angle to the inclined meeting face of the rail 2, and 95 the member or strip 4 is further bent and folded to form a ledge or lip 9, substantially of double thickness, which extends horizontally at an angle to the tongue 8 shown as slightly less than a right angle, and a portion 100 10 of the member 4 extends below and lies in contact with the outer exposed face of the rail 2 and may be secured to the rail by nails or the like.

In operation when the sashes are closed 105 together, as shown in Fig. 1, the tongue 8 enters the groove formed by the member 3 and the rabbet 5, and, because of the opposite inclinations or opposite angular positions of the walls of this slot and of the tongue 8, 110

and also by reason of the fact that when the meeting rails 1 and 2 are brought together by vertical movement in closing the window such movement is in a plane oblique to the 5 surfaces of the rabbet 5 and of the tongue 8, the folded edge of the member 3 will press against the tongue 8 at one side thereof and near its base and the face of the rabbet 5 will press against the other side of the tongue 8 10 adjacent to its free edge, thereby securing a tight seal of the tongue in the groove. Also when the sashes are in closed position the lip 9 overlaps the edge of the rail 1 and fits against the face of the rabbet 6, closing the 15 space between the rails 1 and 2 and closing the mouth of the groove formed by the rabbet 5 and the member 3. Thus the tongue 8 and the lip 9, together with the other coacting parts as above described, provide a 20 double seal between the meeting rails 1 and 2 and effectively exclude wind, rain and dust. Also rattling of the sashes is prevented because of the fact that they are firmly held together by the coacting weather - strip 25 members.

It is obvious that various modifications may be made in the construction shown and above particularly described within the principle and scope of my invention.

30 I claim:

1. A weather-tight joint comprising, in combination with two relatively movable parts, two members, one upon each part, one member at the meeting face of one of 35 the parts and forming a groove therewith, and the other member at the meeting face of the other part and provided with a tongue adapted to engage in the groove formed by the first member and to be pressed 40 in the groove to form a seal and also provided with a lip extending away from the part upon which the member is carried and extending across the mouth of the groove so as to close the mouth of the groove by 45 contact with the other part.

2. A weather-tight joint, comprising, in combination with the meeting rails of a window, one of the rails having a rabbet formed in its meeting face, a member secured flat 50 against the meeting face of the rabbeted rail and projecting beyond the edge of the rabbet thereof to form a groove therewith, and a second member attached to the meeting face of the other rail and provided with a 55 tongue adapted to engage in the groove formed by the first member and to be pressed in the groove to form a seal and also provided with a lip extending at an angle to the tongue and forming a projecting ledge 60 adapted to overlap the edge of the first meeting rail and close the mouth of the groove to form a second seal.

3. A weather-tight joint comprising, in

combination with two relatively movable parts, one of the parts having a rabbet formed in its meeting face, a member secured flat against the meeting face of the rabbeted part and projecting beyond the edge of the rabbet to form therewith a groove, and a second member secured to the meeting face of the other part and provided with a tongue extending from the meeting face and adapted to engage in the groove formed by the first member, the opposite faces of the groove lying at oblique angles to corresponding sides of the tongue, whereby pressure is brought to bear on opposite sides of the tongue by the face of the rabbet at one side and by the first member at the other side and a tight seal thereby secured.

4. A weather-tight joint comprising, in combination with two relatively movable parts, one of the parts having a rabbet formed in its meeting face, a member secured flat against the meeting face of the rabbeted part and projecting beyond the edge of the rabbet to form therewith a groove, and a second member secured to the meeting face of the other part and provided with a tongue extending from the meeting face at an oblique angle and adapted to engage at an oblique angle in the groove formed by the first member, the second member being also provided with a lip extending at an angle to the tongue and adapted to overlap the edge of the first member and close the mouth of the groove.

5. A weather-tight joint comprising, in combination with the meeting rails of a window, one of the rails having a rabbet formed in its meeting face, a sheet-metal member secured flat against the meeting face of the rabbeted rail and projecting beyond the edge of the rabbet to form a groove therewith, a second sheet-metal member secured to the meeting face of the other rail and bent to form a tongue extending obliquely to the meeting face and adapted to engage obliquely in the groove formed by the first member, so that the first member presses on one side of the tongue and the face of the rabbet presses on the other side of the tongue, the second member being also bent to form an extended lip adapted to overlap the edge of the first meeting rail and close the mouth of the groove, the second member also having a portion overlapping the edge of the second meeting rail and secured to the free exposed face thereof, substantially as set forth.

In testimony whereof I have affixed my signature in presence of two witnesses.

JACOB KAMMERER.
